UNITED STATES PATENT OFFICE.

CHARLES A. McDOWELL, OF PRINEVILLE, OREGON.

CURRYCOMB.

1,243,846.

Specification of Letters Patent.

Patented Oct. 23, 1917.

Application filed May 14, 1913. Serial No. 767,645.

To all whom it may concern:

Be it known that I, CHARLES A. McDowell, a citizen of the United States, residing at Prineville, in the county of Crook, 5 State of Oregon, have invented certain new and useful Improvements in Currycombs; and I do hereby declare the following to be a full, clear, and exact description of the invention, such as will enable others skilled 10 in the art to which it appertains to make and use the same.

This invention is directed to improvements in curry combs, and has for its object to so construct a device of this character that the comb teeth may be readily cleaned after the currying operation.

A further object of the invention is to construct a curry comb of this type that the cleaner bars will be held positively against 20 accidental displacement when the curry comb is being used.

With these and other objects in view, this invention resides in the novel features of construction, formation, combination and 25 arrangement of parts to be hereinafter more fully described, claimed and illustrated in the accompanying drawing, in which:—

Figure 1 is a perspective view of the curry comb.

Fig. 2 is a longitudinal sectional view therethrough.

Fig. 3 is a bottom plan view.

Fig. 4 is a detail perspective view of one of the cleaner bars.

Fig. 5 is a fragmental sectional view showing the manner in which the cleaner bars co-operate with the teeth.

Fig. 6 is a fragmental perspective view of one end of one of the cleaner bars.

Referring to the drawing, the numeral 1 designates a curry comb, comprising a back plate 2, to the under surface of which is secured a plurality of comb teeth 3, said comb teeth being U-shaped in cross section 45 and have their bights secured to the back 2 in any well known manner.

The comb teeth are provided at one of their ends with ears 4 and to which are pivoted the ears 5 formed upon the side plates 50 6 of the cleaner bars 7, said plates converging toward and connected to plates 8, which terminate at one of their ends in upwardly

curved extensions 9, said extensions being connected by a bar 10, and to which is connected a loop 11.

The cleaner bars 7 are formed from resilient sheet metal, and the side plates 6 thereof frictionally engage the sides of the comb teeth 3 so that when the loop 11 is grasped and swung outwardly the plates 6 60 will effectually remove the scurf and hair which have collected upon the comb teeth.

Secured to the back 2 and at one end thereof is a loop 12 which registers with the loop 11 so that when the curry comb 1 65 is grasped one of the fingers of the user will engage the loops 11 and 12, thus positively holding the cleaner bars from becoming accidentally displaced.

In this connection it is explained that in 70 common use a comb of this character is, instead of being grasped by the handle 14, grasped by spanning the body 1 of the curry comb and when the comb is used in this manner one of the fingers of the operator 75 will pass through the loop 12 and engages the loop 11 and thus holds the two loops in alinement and the cleaner bars in their inoperative position. It will also be noted that the cleaning of the teeth will be facilitated owing to the fact that it is unnecessary 80 to remove the finger from the loop 11 or employ the other hand to swing the cleaner bars, since all that is necessary is to bend the finger extending through the loop 11 85 and engage and force the transverse bar 10 outwardly. In this manner the cleaning bars may be swung sufficiently to permit of a thorough cleansing of the teeth and by again straightening the finger and pressing 90 against the loop 11 the cleaner bars may be returned to their normal positions.

Secured to the back 2 and to one side thereof is a shank 13 and to which is connected the usual handle 14.

From the foregoing description it will be seen that I have provided a curry comb which can be manipulated to thoroughly clean the comb teeth thereof and one which may be manufactured at a minimum cost. 100

What is claimed is:—

A curry comb comprising a back having a loop extending outwardly therefrom adjacent one end, toothed bars carried by said

back, cleaner bars pivoted to said toothed bars and each consisting of a channeled body portion, the web of each cleaning bar being extended beyond one end thereof and 5 bent so as to project past the plane of said back, and a transverse bar connecting the ends of the curved portions of said webs and having a second loop formed integrally

therewith and arranged to register with the first named loop.

In testimony whereof, I affix my signature, in the presence of two witnesses.

CHARLES A. McDOWELL.
